(57) **CLAIM**

The ornamental design for a kitchen utensil handle, as shown and described.

DESCRIPTION

FIG. 1 is a left side elevational view of a kitchen utensil handle showing my new design, the right side elevational view being a mirror image thereof;

FIG. 2 is a top plan view thereof;

FIG. 3 is a bottom plan view thereof;

FIG. 4 is a rear elevational view thereof;

FIG. 5 is a front elevational view thereof;

FIG. 6 is a cross-sectional view taken along line 6—6 in FIG. 2;

FIG. 7 is a cross-sectional view taken along line 7—7 in FIG. 1;

FIG. 8 is a cross-sectional view taken along line 8—8 in FIG. 1;

FIG. 9 is a cross-sectional view taken along line 9—9 in FIG. 1; and,

FIG. 10 is a perspective view thereof.
